UNITED STATES PATENT OFFICE.

ALBERT BROD, OF NEW YORK, N. Y.

DESIGN FOR A RING OR SIMILAR ARTICLE.

Application filed March 28, 1925. Serial No. 12,921. Term of patent 3½ years.

To all whom it may concern:

Be it known that I, ALBERT BROD, a citizen of the United States of America, residing at New York city, county and State of New York, have invented a new, original, and ornamental Design for a Ring or Similar Article, of which the following is a specification, reference being had to the accompanying drawing, forming part hereof, in which Fig. 1 is a side elevation of a ring showing my new design, and Fig. 2 is an edge view thereof.

I claim:

The ornamental design for a ring or similar article, as shown.

Signed at New York city, N. Y., this 25th day of March, 1925.

ALBERT BROD.
